UNITED STATES PATENT OFFICE

2,104,656

WIRE TENSION CONTROLLING DEVICE

Robert F. Krejci, Cleveland Heights, Ohio, assignor to General Electric Company, a corporation of New York

Application September 28, 1934, Serial No. 745,862

1 Claim. (Cl. 242—45)

My invention relates to apparatus for controlling the tension of wire in wire-working and treating machines, and more particularly to apparatus for governing the amount of wire unreeled and the tension of said wire in said machines. Wire tension controlling means are particularly desirable in wire working and treating machines, especially when a fine or coiled wire is being used, as more accurate control of their operations is provided and less danger of deformation and injury is presented. Such means are necessary in the annealing of incandescent lamp filaments, the operation of which consists in drawing through an annealing furnace, from one spool to another, a mandrel having the filament coiled thereabout. The mandrel and filament coil assembly is so fine as to be easily distorted by the high annealing heat so that means are provided, in combination with tension controlling apparatus of my invention, for winding and unwinding the wire assembly from the spools. When winding and unwinding means are provided, some means such as that of my invention is required to compensate for the change in rate of movement of the wire with the spools filled and nearly empty.

One object of my invention is to provide means for controlling the tension of wire in wire working and treating machines. Another object of my invention is to provide wire tension controlling apparatus in combination with wire unreeling means. Another object of my invention is to provide wire tension controlling apparatus capable of exerting a very small tension force and of such low inertia as to be very responsive.

In the drawing, Fig. 1 is a diagrammatic view showing the apparatus of my invention in combination with a filament coil annealing machine; Figs. 2 and 3 are end and sectional views of the switch assembly of the apparatus of my invention; and Fig. 4 is a perspective view of the switch used in said assembly.

In the machine shown, the wire 10, which is comprised of a mandrel with the incandescent lamp filament coiled therearound, is unwound from spool 11 and passes over sheaves 12 and 14 and under sheave 13. From sheave 14 the wire passes through the annealing furnace 15 and then onto the spool 16. All spools and sheaves are mounted in a fixed position with respect to the furnace 15 except for sheave 13 which tends to swing out of the direct path of the wire to take up the slack and produce the tension required. Both spools 11 and 16 are driven, the latter from shaft 17 which is turned by jack shaft 18 through gears

19—20, rod 21 and gears 22—23, and the former by shaft 24 which is turned by said jack shaft 18 through two pairs of gears 25—26 and 27—28 at greater and less speed respectively than spool 16. The selection of the driving pair of gears 5 for the spool 11 is controlled by the vertical position of sheave 13 which causes the unreeling speed to be increased and decreased when it reaches its upper and lower limits of movement respectively. The sheave 13 is mounted on arm 10 29 which extends from hub 30 of the switch assembly pivotally mounted on the screws 31 and 32 of bracket 33. The hub 30 is provided with an arm 34 extending in the opposite direction to arm 29 on which a weight 35 is mounted which 15 partially counteracts the weight of arm 29 on sheave 13. Enclosed within the hub between the end pieces 36 and 37 thereof is located the mercury switch 38 which is mounted in the gaskets 39 and 40 on the axis of rotation of the assembly. The mercury switch 38 is preferably of the type manufactured by the General Electric Vapor Lamp Company under the trade name Kon-nector and comprises a glass envelope 41 which is divided by the porcelain partition 42 into two 20 sections. Each section holds a pool of mercury 43 which contacts the inner end of an inlead 44. The function of the switch is to make and break the electrical circuit between inleads 44—44 by allowing the mercury pools to flow together and 25 flow apart through an offset hole 45 in the partition 42 as the switch is turned. As the upper limit of movement of sheave 13 is reached, the switch is turned so the pools of mercury flow together through the hole 45 in the partition 30 42 completing the circuit, and as the lower limit of movement of sheave 13 is reached, the switch is turned so the pools separate, breaking the circuit. In this application about 30° of movement is provided since the cohesion of the mercury tends to keep the pools from flowing together and then after they are joined, tends to keep 35 them together.

During the period the circuit through the switch is open, spool 11 and shaft 24 are driven by 45 gears 27 and 28 through the clutch 46 since the direction of motion is such as to wedge the rollers 47 between the cam 48 and the roll 49. This arrangement unreels the wire 10 from spool 11 at a slower rate than it is reeled up by spool 16 so 50 that sheave 13 will gradually raise until the circuit through switch 38 is closed. The circuit through the switch includes the solenoid 50 which is operated as the circuit is closed causing the armature 51 thereof to be moved. The armature 55

engages arm 52 which turns rod 53 causing arm 54 thereon to slide gear 25 on shaft 24 so the dogs thereof engage the dogs of collar 55. The gears 25 and 26 are constantly in mesh and are of such size as to turn shaft 24 more rapidly, causing the clutch 46 to be released since the rollers 47 thereof come below the more cut away portion of cam 48. The rate of rotation of spool 11 is now slightly greater than that of spool 16 so the sheave 13 falls slightly. This method of operation takes care of the change in the amount of wire wound and unwound from the spools when they are full and nearly empty, as well as all other discrepancies in feed.

15 What I claim as new and desire to secure by Letters Patent of the United States is:

In an apparatus of the type described, the combination of an unwinding spool adapted to hold wire and a winding spool adapted to receive 20 said wire, means for driving said winding spool, clutch means for driving said unwinding spool at a slower speed than said winding spool, an-

other clutch means for driving said unwinding spool at a higher speed than said winding spool, a sheave engaging said wire between said spools and movable in a substantially vertical plane for taking up the slack in said wire, electro-magnetic means engaging said second-mentioned clutch means, an electric circuit including said electro-magnetic means and a switch means adapted to be closed by the upward movement of said sheave to actuate said electro-magnetic means and bring 10 into engagement said second-mentioned clutch means to drive said unwinding spool at a higher speed than said winding spool, and said switch means being adapted to be opened by the downward movement of said sheave to actuate said 15 electro-magnetic means and cause said second-mentioned clutch means to be disengaged and bring into engagement said first-mentioned clutch means to drive said unwinding spool at a slower speed than said winding spool thereby 20 maintaining a uniform tension in said wire.

ROBERT F. KREJCI.
